CLAIM

The ornamental design for a bottle, as shown and described.

DESCRIPTION

FIG. 1 is a front elevational view of a bottle according to a first embodiment of the present invention.

FIG. 2 is a rear elevational view of the bottle of FIG. 1.

FIG. 3 is a left side elevational view of the bottle of FIG. 1.

FIG. 4 is a right side elevational view of the bottle of FIG. 1.

FIG. 5 is a top plan view of the bottle of FIG. 1.

FIG. 6 is a bottom plan view of the bottle of FIG. 1.

FIG. 7 is a sectional elevational view taken along line 7-7 of FIG. 5.

FIG. 8 is a three-quarter view of the bottle of FIG. 1.

FIG. 9 is a front elevational view of a bottle according to a second embodiment of the present invention.

FIG. 10 is a rear elevational view of the bottle of FIG. 9.

FIG. 11 is a left side elevational view of the bottle of FIG. 9.

FIG. 12 is a right side elevational view of the bottle of FIG. 9.

FIG. 13 is a top plan view of the bottle of FIG. 9.

FIG. 14 is a bottom plan view of the bottle of FIG. 9.

FIG. 15 is a sectional elevational view taken along line 15-15 of FIG. 13; and,

FIG. 16 is a three-quarter view of the bottle of FIG. 9.

The dashed lines illustrate environment that does not form a part of the present invention, and no claim is made to the material illustrated with dashed lines.
